UNITED STATES PATENT OFFICE.

AXEL EKSTROM, OF BALLSTON SPA, NEW YORK, ASSIGNOR TO CORNELL S. HAWLEY,
OF BOSTON, MASSACHUSETTS.

RAILWAY-CAR.

1,071,304.

Specification of Letters Patent. Patented Aug. 26, 1913.

Application filed May 18, 1913. Serial No. 767,291.

To all whom it may concern:

Be it known that I, AXEL EKSTROM, a citizen of the United States, residing at Ballston Spa, in the county of Saratoga and State of New York, have invented certain new and useful Improvements in Railway-Cars, the following being a full, clear, and exact disclosure of the one form of my invention which I at present deem preferable.

For a detailed description of the present form of my invention, reference may be had to the following specification and to the accompanying drawings forming a part thereof, in which,

Figure 1 is a side elevation of my car; Fig. 2 is a side elevation and Fig. 3 a plan of the under framing forming a truck.

My invention relates to cars particularly adapted for street service or other situations involving severe corners.

It consists in a four-wheel car having a depending body portion with side doors therein included between the two car axles and extended ends overhanging the side axles. This arrangement is to be contrasted with side-door cars supported on swivel trucks at each end, in that my construction permits of a deep and short framework between the axles which takes the supporting strain, while the extended overhanging ends can be comparatively light. Thus I am enabled to save in the amount of steel required for the car and also in weight.

Turning to the drawings, A represents the car body and B the central depending portion thereof between the axles α α with the side doors D D therein and the car sides projecting down outside the wheels. The doors open into a depressed central space within the car from which one or more steps lead to the floor level of the extended ends. The car body is shown as resting on a truck frame. This comprises the side-bars E and F depressed below the depending portion B and jointed on a horizontal axis at e and f respectively and also jointed at those points to blocks E¹ and F¹ which bear against the under side of the car body preferably through interposed springs. The side bars are connected by end bars G, G¹, also by cross bars H and H¹, while the cross bars K, K¹ receive between them the depending portion B of the car body and brace it against the axles on either side through the

side frames and the pedestals E² and F² which embrace the journal boxes on the respective axles. Four springs S on the corners of the frame aforesaid support the car body while the propelling motors M are spring supported as shown on the cross bars extending between the side bars E, F and centered on the axles α , α , so as to be supported outside of the said axles respectively and geared thereto. The above described frame tends to prevent vertical oscillation of the overhanging ends.

Brakes J are provided which bear on the inside surfaces of the wheels W between those wheels and the depending portion B of the car body.

Beside the advantage mentioned heretofore my construction tends to bring the center of gravity of the car close to the wheels and axles to which both the starting and stopping forces are applied. This avoids a difference in pressure of the wheels on the track as well as jarring of the car body at starting and stopping. I also put all of the weight on the driven axles with only two motors while the extended ends permit the use of a car as long as those which ordinarily require two swivel trucks which must have four motors if all the axles are to be driven. Other desirable features will be apparent.

What I claim as new and desire to secure by Letters Patent is:

1. A four-wheel railway-car, having a depending portion between the two car axles provided with side doors and extended ends overhanging said axles.

2. A four-wheel railway-car, having a depending portion between the two car axles provided with side doors and extended overhanging ends, the said depending portion being braced longitudinally against the respective axles.

3. A four-wheel railway-car, having a depending portion between the two car axles provided with side doors, extended ends overhanging the said axles and propelling motors supported outside of and geared to the said axles respectively.

4. A four-wheel railway-car, having a depending portion between the two car axles provided with side doors, extended ends overhanging the said axles, propelling motors supported outside of and geared to said axles respectively and brakes between said depending portion and the wheels, whereby

the point of application of force in stopping or starting is brought nearer to the center of gravity of the car.

5. A four-wheel railway-car having a depending portion between the two car axles provided with side doors with the car-body supported on an axle-supported frame centrally jointed on a horizontal axis and having springs interposed between the car-body 10 and the ends of said frame which extend beyond the said axles.

6. A four-wheel railway-car having a depending portion between the two car axles with side doors therein and provided with a 15 frame between the axles and car-body which

has its side bars depressed below the said depending portion.

7. A four-wheel railway-car having a depending portion between the car axles provided with side doors, extending end portions overhanging the said axles and car sides projecting down outside of the wheels.

In witness whereof I have hereunto set my hand, before two subscribing witnesses, this 8 day of May, 1913.

AXEL EKSTROM.
